(57) **CLAIM**

The ornamental design for a laser scanner, as shown and described.

DESCRIPTION

FIG. 1 is a perspective view of a laser scanner constructed in accordance with the invention;

FIG. 2 is a front view of the laser scanner shown in FIG. 1;

FIG. 3 is a rear view of the laser scanner shown in FIG. 1;

FIG. 4 is a left side elevational view of the laser scanner as shown in FIG. 1;

FIG. 5 is a right side elevational view of the laser scanner shown in FIG. 1;

FIG. 6 is a top elevational view of the laser scanner shown in FIG. 1; and,

FIG. 7 is a bottom elevational view of the laser scanner shown in FIG. 1.
